COMMINUTED FUEL BURNER

Filed Aug. 6, 1928

Inventor

Ralph Henry Burdick

By *Thomas B. Lyman*
Attorney

UNITED STATES PATENT OFFICE

RALPH HENRY BURDICK, OF PORTLAND, OREGON

COMMINUTED-FUEL BURNER

Application filed August 6, 1928. Serial No. 297,710.

My invention relates to comminuted fuel burners and is more particularly adapted to the burning of saw dust, and other comminuted forms of mill waste as hog fuel and the like.

The invention consists primarily of a metal hopper, having a removable bottom, and having inwardly extending end adapted to insertion within the door of the existing heating plant, and having a removable hopper for maintaining the fuel as a supply therein and that feeds by gravity into the fire chamber of the device. Means being provided for regulating the draft passing through the fire or a heat chamber of the device.

The primary object of my device consists in a simplified construction and one that may be easily and quickly installed and in use.

A further object of my device consists in a simplified construction that is cheap in construction, dependable in operation, and one that may be used for the burning of comminuted mill waste fuels over relative long periods with freedom of attention, alteration and repair.

Still further objects of my invention reside in a device that may be used in the economic generation of heat and having a relatively low first cost of operation and that may be used for the generation of heat at low cost.

And still further objects of my invention consists in a construction that permits of the using of cheap materials and relatively cheap labor in the manufacture that results in a product having a low first cost of production.

With these and incidental objects in view, the invention consists in certain novel features of construction and combination of parts, the essential elements of which are set forth in the appended claims, and a preferred form of embodiment of which is hereinafter shown with reference to the drawings which accompany this specification.

In the drawings:—

Fig. 1 is a sectional, side elevation of the assembled device, shown installed in combination with a standard heating furnace, with the shell of the furnace partially broken away to illustrate the construction of the same and how the same is to be installed.

Fig. 2 is a perspective, end view, of the disassembled devices, showing the construction of the different units of the device and how the same may be assembled to complete the

55

Fig. 3 is a cross section view, taken on line 3—3 of Fig. 1, looking in the direction indicated.

Like reference characters refer to like parts throughout the several views.

60

My new and improved device is primarily intended to be used in combination with existing heating plants. I preferably form the body portion of my device of side walls 1 and 2, and a front wall of two portions, a horizontal portion 3, and a vertical portion 4. The rear wall 5 is placed between the side wall elements. I have found best results obtained wherein the side front and rear walls are welded together at their meeting edges to form a box like structure that is homogeneous and that will not permit air to leak thereinto. Instead of forming the bottom of grates as heretofore has been the general custom, I have found excellent results obtain

65

wherein the bottom 6 is also made of sheet steel and that is placed between the side walls and the outer end of the same resting upon a supporting rod 7 that passes through the side walls, this rod acting as a support for the bottom of the fire box and at the same time being so placed that the side walls may be pulled into intimate contact with the bottom element and be maintained in position there-

70

between. In order that the bottom may be placed in desired position and at the desired angle relative to the furnace with which the device is to be placed, I recommend that an adjustable support of refractory materials, as fire brick 8, be placed within the furnace 9, and rest upon the supporting grates thereby forming a rest for the inner end of the bottom. The primary purpose of making the bottom 6 removable and adjustable is to per-

75

mit the removal of the same for renewable purposes and at the same time to provide for an adjustment with existing furnaces. An air damper 10 is provided at the front end of the device that is in hinged relation with the side walls 1 and 2. The supporting rod 11

80

100

of the draft regulator 10 passes through one of the side walls and terminates in a lever 12 that may be manually or automatically adjusted and positioned through the medium of an actuating chain 13 terminating at a convenient point for manual manipulation. The inner surface of the draft regulator contracts with the inner edge 14 of the bottom element and acts as a stop for the same. This forms a substantially air tight connection between the draft regulator and the bottom element and excludes air from the combustion chamber through the draft entrance.

For the purpose of inspection and the removal of the products of combustion, I make the hopper 15 removable. A ledge 16 is disposed about the outer surface of the hopper and in spaced relation with the lower edge 17 of the hopper. The lower end of the hopper 20 should be accurately made to permit of entry of the hopper into and between the upper end of the box like structure composing the fire box. Locking holes 18 and 19 are disposed through one of the walls of the fire box into 25 which the locking lugs 20 and 21 are made to engage. The engagement of the locking lugs with the locking holes prevents the undue removal of the hopper from the fire box, and the ledge 15 fitting tightly upon the upper 30 edge of the fire box prevents the undue entry of air in appreciable quantities into the fire box. I have made many installations of saw dust burners as herein outlined and have found that the same give excellent results.

35 While the form of the device herein shown and described is admirably adapted to fulfill the objects primarily stated, it is to be understood that it is not intended to confine the invention to the one form of embodiment herein shown and described, as it is susceptible of embodiment in various forms all coming within the scope of the claims which follow.

What I claim is:

1. In a device of the class described, the combination of a fire box having side walls and a front wall and a rear wall made of sheet metal and fused together at their meeting edges, a cross bolt passing through the side walls to form the support for a removable 45 bottom and to act as a tightener for maintaining a tight working relation between the side walls and the bottom, a draft regulator hingedly positioned between the side walls and adapted to rest upon the front wall of 50 the removable bottom, and a removable hopper having a ledge disposed about its outer lower surface and in spaced relation with the lower edge of the hopper the lower end of the 55 said hopper adapted for entry into the upper entry of the fire box to permit the ledge disposed therearound resting upon the upper edge of the fire box walls and means for locking the hopper relative to the fire box.

2. In a device of the class described, the 60 combination of a fire box made of sheet metal

and fused together at its meeting edges, a removable and adjustable bottom of sheet metal forming the bottom of the fire box and disposed between the side walls of the fire box, means for clamping and supporting the bottom relative to the side walls and a removable hopper adapted for supporting a fuel supply immediately above the fire box with a communicating passageway leading from the hopper into the fire box and means for locking the hopper relative to the fire box.

3. In a device of the class described, the combination of a sheet metal fire box, an adjustably removable sheet metal bottom disposed between the side walls of the fire box, means for supporting the bottom and clamping the same relative to the side walls, a draft regulator disposed between the rear wall and the bottom and hinged relative to the side walls and a hopper communicating with the inner space of the fire box and means for locking the hopper relative to the fire box walls.
